WEB ASSEMBLING MEANS FOR PRINTING PRESSES

Edmund W. Dean, Battle Creek, Mich., assignor
to Duplex Printing Press Company, Battle Creek, Mich., a corporation of Michigan

Application April 19, 1937, Serial No. 137,856

15 Claims. (Cl. 270—5)

This invention is an improvement in newspaper web printing presses and its object is to enable a web printed on any one unit of the press, and bearing some special feature, to be assembled or associated with any other web printed on some other unit of the press instead of being confined as heretofore to that relative position in the final assembly of the webs in which it would ordinarily appear.

10 The web bearing the special featured page is usually arranged so that such page will appear as the title page, or page 1 of the finished paper, but at times it is desirable to divert at least such special feature page to some other portion of the finished product, and my invention provides a means to do this.

To facilitate an understanding of the invention it should be understood that newspapers consisting of a large number of pages are usually delivered in sections. Some of these sections contain pages which have special features which differentiate them from the usual newspaper page. These features may be half tone cuts, additional colors, or matter printed by a different type of printing from the remainder of the paper. These features may be required on the title page, (page 1), or on the first page of any section of the paper, or they may be required on an inside page of any section of the paper.

30 The modern newspaper press usually embodies a number of perfecting units each capable of producing from four to eight perfected pages according to whether the plate cylinders are two-plate or four-plate long. Usually in a four-plate wide press each printing unit or deck has associated with it a group of angle bars to divert one longitudinal section of the web out of the straight line passage to the folder and place such diverted section of the web over or under the remaining straight running section, both sections being then led to the folder. If the usual style of four-page wide newspaper presses is operated at full capacity, each perfecting unit will print eight pages, four on each longitudinal section of the web, and these may be run to and through the folder and delivered as separate eight-page papers; or the webs may be combined with the webs printed by other units and delivered in sections each containing more than eight pages up to the full page capacity of the press.

With the customary two former folder, two sections only can be delivered on "straight" run, or four sections when running "collect". When the entire product is folded together (book fold)

there will be no question of sections, but the ability to place "special" pages in various positions is equally valuable.

One unit or deck of the press may be equipped with mechanism to print special page features as mentioned above. This special unit usually has its product delivered to the folder to appear on the title page, or page 1 of the finished product; but as stated it is advantageous at times to be able to divert at least such special pages to some other position in the finished product. Heretofore this has not been practical, but my invention enables this to be done by diverting the web or section of the web bearing such special feature page to the line of the section of the web with which it is to be assembled prior to reaching the folder.

For this purpose I provide a leading in roller adjustable in position and related roller and angle bars where a web section from any unit may be associated with a web section from any other unit. To enable others to understand and use the invention I will explain the same with reference to the accompanying drawings and summarize in the claims the essentials of the invention and novel features of construction and novel combinations of parts for which protection is desired.

The drawings show the angle bar assembly of a six unit (or six deck) newspaper printing press 30 4 pages wide, and as usually furnished there is one set of angle bars (consisting of two bars) for the product of each unit. Such angle bars are preferably placed between the printing units and the folder.

In said drawings:—

Fig. 1 is a side elevation of part of a six unit or six deck newspaper printing press and folder, partly broken away, to show the angle bar or sheet assembly section of such press equipped with my invention.

Fig. 2 is a top plan view of the usual angle bar, or sheet assembly, section of a six unit or six deck press equipped with one embodiment of my invention.

Fig. 3 is a side elevation of Fig. 2, the side frames being omitted.

Fig. 4 is a right hand end elevation of the assembly shown in Fig. 2.

Fig. 5 is a right hand side elevation of Fig. 4.

Fig. 6 is a detail top plan view of the sheet assembly shown in Fig. 1 with a further embodiment of my invention.

Fig. 7 is a side elevation of the assembly showing the adjustable web deflecting rolls.

The printing mechanism may be of any suitable construction, either of the "unit" type, or the superposed deck type. To simplify explanation of my invention I have shown and will describe it as used in connection with a multi-unit press having six web perfecting units A, which are substantial duplicates, a folder F, and an angle bar or web assembly section B located between the printing units and the folder. Each unit A is adapted to print a web, which webs are led from each unit to the assembly unit and thence to the folder in the usual way. The web assembly mechanism shown is for a press capable of producing a newspaper of 48 pages from six four-page wide webs (W, W2, W3, W4, W5, W6) printed on plate cylinders four pages wide (folder not collecting). Each four-page wide web is led from the related printing unit A of the press to a guide roller 2 adjacent the assembly section, and at or adjacent its related roller 2 each web is slit longitudinally by a slitter 3; and then customarily in ordinary machines one longitudinal section of the web (as Wb, Fig. 2) is led directly to and over a guide 12 at the opposite side of the assembly mechanism to the usual assembly roller 20 at the top of the folder by which the assembled sections of the web are directed to the folder and thereby folded longitudinally in the usual manner.

In Fig. 4 I have shown rolls with slitters 3 only at the upper group of angle bars (for web W) and at the fourth group (for web W4). The slitter mechanisms for the other groups being omitted in order to more clearly show the additional angle bars 9.

In the drawings my invention is shown as applied to a four-page wide press, but it would be just as useful applied to a two-page wide press.

Heretofore the other longitudinal section Wa of the web W is led to and over an angle bar 4a by which it is deflected at right angles and then led beneath the web section Wb to and over a second angle bar 4b (parallel with bar 4a) by which it is again deflected at right angles parallel with and below section Wb and directed, together with web Wb, to and over roller 12, and thence to the folder.

A similar set of angle bars (such as 4a, 4b above described) is provided for each web, as indicated in Fig. 2; said angle bars being supported on transverse rods or bars 1a attached to side frames 1, as indicated in Figs. 2 and 4, and ordinarily each of the webs W, W2, W3, W4, W5 and W6 (Fig. 3) coming from its related printing mechanism is divided and its sections assembled in the same manner as above described web W.

As thus far described the construction is old. In my invention I provide a roller 6 at one side of the assembly B in the plane of one of the angle bars 4a. As shown in Figs. 2 and 5 roller 6 is journaled in brackets 6a, which may be fastened to the side frame 1 in fixed position. The brackets 6a may also form bearings for the upper ends of vertical screw rods 8; the lower ends of which are journaled in brackets 8a (Figs. 4 and 5) which are fixed to the side frame 1. Bevel gears 8b may be mounted on the lower ends of the screw rods 8 and mesh with bevel gears 8c mounted on a horizontal shaft 8f journaled in brackets 8d fastened to frame 1. The shaft 8f may be provided with means for revolving it, a crank 8e being shown for manual

operation, but a motor drive may be utilized for more rapid movement.

Parallel with roller 6 is an adjustable roller 7 which is shown as journaled in brackets 7a threaded onto screw rods 8, the bases of the brackets preferably having a sliding engagement with the adjacent frame 1 and having tongues 7c sliding in grooves 1a in the frame 1 (Fig. 4).

I also provide a third angle bar 9 for each group of angle bars 4a, 4b below the top group, each bar 9 being arranged at right angles to the bars 4a, 4b (see Fig. 2) and at the side of the frame adjacent roller 6.

By revolving shaft 8f screws 8 can be revolved 15 to raise or lower the brackets 7a and move roller 7 to a position opposite the desired group of angle bars. Roller 7 may be locked in adjusted position by pins 7b entered into holes 1b in the frame members 1. The roller 6 may be also adjustable like roller 7 as hereinafter described.

When the webs are led in the usual manner, the web section Wa will be led to the folder under web section Wb. But if desired the side roller 7 can be adjusted to a position opposite one of the lower groups of rollers, for example as shown in Fig. 4, and the web section Wa led from the angle bar 4a to and over roller 6 and down under roller 7 and then led inward to and over the angle bar 9 of the third group of angle bars and then to the folder between the sections of web W3. By properly adjusting roller 7 web Wa can be assembled with any other web sections than web section Wb, for instance as shown in dotted lines in Fig. 4 the roller 7 is 35 positioned to direct web section Wa into association with the lower web W6.

The rollers 12 to 12k in Fig. 3 are for guiding the separate webs to the folder. For some products, a web is run full width (4 pages wide in 40 a 4-page-wide press) on the way to the drag roll over the folder and slit at or near that roll. For other products each web will be slit as shown in the drawings, one portion running straight line to the folder and the other portions using angle bars. Still other products run the webs using both the above sets; for this reason I have shown enough rollers in Fig. 3 to provide one guide for each half web as usually used and one extra guide (13 to 13e) for each 50 printing unit to guide the web from the special printing unit at each of the positions to which it may be led. As there are about 250 different products or arrangements of pages etc., that can be produced on an octuple press provided with 55 two folders and two additional formers (air plane former), there must be provided means to carry every half web printed to the folder.

In the ordinary press each of the webs W to W6 would be split and assembled together in the 60 same manner that the upper web would be assembled. For instance, in Fig. 3 the web Wa is diverted but Wb runs horizontally to the top of roll 12; the roll just under roll 12 is not used when the web Wa is diverted but is in place to 65 use if the web Wa were run over both angle bars, the top of this roll being aligned with the angle bar 4b. On the next deck below half webs Wd and Wc are shown as using their guide rolls but there is a roll in position to receive a web from 70 the extra angle bar which is not used until the web Wa is diverted to use this bar.

As shown in Figs. 2-5 the sections of the upper web can be associated with any section of a lower web or vice versa, but by providing proper 75

rolls any one of the lower webs **W6** to **W2** could be associated with any of the other lower webs **W2** to **W6**. For instance as shown in Figs. 6 and 7 roller **6** could be made adjustable as well as roller **7**, and such association could be made; that is, the webs **W6** and **W3** could be associated, or **W5** and **W2** etc. As shown in Figs. 6 and 7 the roller **6** is journaled in bearings **60**, which may be similar to bearings **7a** of roller **7**, and 10 **60** is slidable in ways parallel with the ways of bearings **7a**. The bearings **60** are adjustable by means of screws **61** which are journaled in brackets **62** and **63** attached to the side frame **1**. Bevel gears **64** attached to upper ends of screws **61** 15 mesh with bevels **65** on a shaft **66**, journaled in brackets **67** on frame **1**, and by rotating shaft **66** the roller **6** can be raised or lowered independently of roller **7**. With this arrangement a web or section of any web can be diverted and 20 directed to and assembled with a section of any other web.

As shown the section of the web **W** might be led over roll **6** and by properly locating roller **7** assembled with any of the other web sections. 25 Also by properly adjusting roller **7** a section of any web **W** to **W6** may be directed over roll **7** up over roll **6** and then over the upper angle bar **9** and assembled with the section of the web **W**, that is, that the web from one of the lower sections 30 could be led up to the upper section in the same manner that the web is described as led from the upper section to one of the lower sections but in the reverse direction. For practical reasons the paper will run to better advantage from the top 35 roll to the lower position than from the lower position to the top. In order to reverse the direction another angle bar **9** could be added to each upper group of angle bars.

My invention can be installed in one special 40 unit in a press whereas without my invention it would be necessary to install more than one unit to get the same result. My invention therefore eliminates the costs of such additional machinery as well as requiring much less space in order to 45 accomplish the desired variation in web assemblies.

I claim:—

1. For a newspaper printing press adapted to 50 print a multiple of webs; means whereby the web sections may be aligned before being folded, and adjustable means cooperating with any of said aligning means whereby any web may be diverted and led to and associated with another web before folding.

55 2. For a newspaper printing press adapted to print a multiple of webs and having means whereby each web may be split; and means whereby the web sections may be aligned before being folded; and adjustable means cooperating with any of said aligning means whereby any web section may be diverted and led to and associated with a section of another web before folding.

3. Web diverting means for newspaper printing presses having a multiple of printing units; 60 said means including an angle bar for each web and adjustable web guides at one side of the means cooperating with any of said angle bars whereby any web may be directed to and associated with another web prior to the folding thereof.

65 4. Web diverting means for newspaper printing presses having a multiple of printing units; said means including a set of web diverting angle bars for each web and adjustable web guides at 70 one side of the means cooperating with any of said

sets of angle bars whereby any web may be directed to and associated with another web prior to the folding thereof.

5. For a newspaper printing mechanism having a plurality of web printing mechanisms and 5 means for folding the webs; a web diverting unit interposed between the printing means and the folding means, said unit comprising a plurality of sets of angle bars and a pair of relatively adjustable guides at one side of the unit cooperating 10 with any of said sets of angle bars whereby any web may be diverted from its normal path and directed to and assembled with another web before reaching the folding means.

6. For a newspaper printing mechanism having 15 a plurality of web printing mechanisms and means for folding the webs; a web diverting unit interposed between the printing means and the folding means, said unit comprising a plurality of sets of angle bars, one set for each web, and a 20 pair of relatively adjustable guides at one side of the unit cooperating with any of said sets of angle bars, whereby any web section may be diverted from its normal path and directed to and assembled with another web section before reaching 25 the folding means.

7. A web diverting unit for multiple web printing machines; said unit comprising a plurality of superimposed sets of angle bars, one set for each web section, a roller at one side of the unit arranged at right angles to the normal path of the webs, a second roller parallel with the first at the same side of the unit, and means for relatively adjusting the rollers to cooperate with any of said sets of angle bars whereby any web section can 30 be diverted from its normal path and associated with a section of another web before the sections are folded.

8. In combination with a plurality of printing 35 units and a folder; means interposed between the printing units and folder whereby the webs may be aligned before being folded, and adjustable means cooperating with any of said aligning means whereby any web may be diverted and led to and associated with another web before folding.

9. In combination with a plurality of printing 40 units, a folder, means whereby each web may be split; and web assembly means whereby the web sections may be aligned before being folded; and 50 adjustable means cooperating with any of said aligning means associated with the assembly whereby any web section may be diverted and led to and associated with a section of another web before folding.

10. In combination with a plurality of printing 55 units and a folder; web diverting means interposed between the printing units and folder, said means including an angle bar for each web, and adjustable guides cooperating with any of said 60 angle bars whereby any web may be directed to and associated with another web prior to the folding thereof.

11. In combination with a plurality of printing 65 units and a folder; web assembling means interposed between the printing units and folder; said means including a set of angle bars for each web, and adjustable web guides cooperating with any 70 of said sets of angle bars, whereby any web may be directed to and associated with another web prior to the folding thereof.

12. In combination with a plurality of printing 75 units and means for folding the webs; a web assembly interposed between the printing means and the folding means, said assembly including a

plurality of sets of angle bars, and a plurality of adjustable web guides cooperating with any of said sets of angle bars whereby any web may be diverted from its normal path and directed to and assembled with another web before reaching the folding means.

- 5 13. In combination with a newspaper printing press having a plurality of web printing mechanisms, means for slitting webs, and means for folding the webs; a web assembly unit interposed between the printing mechanism and the folding means, said unit including a set of angle bars for each web and a pair of adjustable guides at one side of the normal path of the webs cooperating with any of said sets of angle bars, whereby any web section may be diverted from its normal path and directed to and assembled with another web section before reaching the folding means.
- 10 14. In combination with a plurality of printing units and a folder; a web assembly interposed between the printing units and folder, said assembly including superimposed sets of angle bars, one set for each web, a roller arranged at right
- 15 20

angles to the normal path of the webs at one side of the unit, a second roller parallel with the first at the same side of the unit, and means for independently adjusting the said rollers to cooperate with any of said sets of angle bars, whereby any web can be diverted from its normal path and associated with another web before they are folded.

15 16. In combination with a newspaper printing press having a plurality of printing units, a folder, web slitting means and a web assembly interposed between the printing units and folder; of a plurality of superimposed sets of angle bars in the assembly, one set for each web, a roller arranged at right angles to the normal path of the webs at one side of the assembly, a second roller parallel with the first at the same side of the assembly, and means for independently adjusting the said rollers to cooperate with any of said sets of angle bars, whereby any web section can be diverted from its normal path and associated with another web before they are folded.

EDMUND W. DEAN.
